UNITED STATES PATENT OFFICE.

SIDNEY C. SLADDEN, OF NEW YORK, N. Y.

FLUID TRACTOR MOTOR.

1,425,292.

Specification of Letters Patent. Patented Aug. 8, 1922.

Application filed February 14, 1921. Serial No. 444,992.

To all whom it may concern:

Be it known that I, SIDNEY C. SLADDEN, a citizen of the United States, and a resident of New York city, in the county and State of New York, have invented certain new and useful Improvements in a Fluid Tractor Motor, of which the following is a full, clear, and exact description.

Among the principal objects which the present invention has in view are: to provide a self-propelling motor for clearing the side walls of pipes, conduits and other passages; to utilize the propelling force of a column of fluid for operating a rotary element adapted to clean or remove obstructions in subterranean or other fluid-filled passages; and to provide suitable means for removing the encrustations or adhesions from boiler and other tubes.

20 Drawings.

Figure 1 is a side elevation partly in section of a motor constructed and arranged in accordance with the present invention, the same being shown as actively mounted on a hose pipe;

Figure 2 is a cross section of the same, the section being taken on the line 2—2 in Figure 1.

As seen in the drawings the motor has a mushroom-like head 7 and a series of openings 8 in the overhanging portion of the head 7. The interior of the head 7 is arranged to provide a curved passageway from the tubular neck 9 to the said openings 8. This is accomplished by providing the interior with an inverted crest 10 the apex whereof is coincident with the axis of the neck 9. From the point of the crest 10 the inner wall of the head 7 is curved through the openings 8, the purpose of the curved wall being to return the fluid passing through the neck 9 in paths parallel to the axis of the neck 9 but flowing in a reversed direction.

The neck 9 is preferably rigid on a coupler 11, which is screw threaded and connected to a hose pipe 12.

Rotatably mounted on the neck 9 is a collar 13. The collar 13 shown in the accompanying drawings has a series of scraper blades 14, the blades 14 being disposed in angular relation to the axis of the neck 9 to present inturned surfaces in the path of the fluid as the same is emitted from the openings 8 in the head 7.

The blades 14 are preferably constructed of thin flat resilient metal, such as steel. The blades are preferably disposed in tiers, each tier extending slightly beyond the preceding or advanced tier, thereby offering successively a larger area for operation. The rotary brush thus formed has been found efficacious in cleansing boiler tubes and similar conduits and for removing the scale or encrustation formed thereon.

In the operation of the motor constructed and arranged as herein disclosed the fluid under pressure is delivered to the interior of the head 7 through which it flows smoothly, being parted in the center by the crest 10 and carried by the wall to the various openings 8, to be there emitted for impingement upon the blades 14. The blades 14 may be multiplied or subtracted from as desired to increase or diminish the effectiveness of the impacts which they exert upon the surface being cleared or cleansed by them.

It will be understood that the speed with which the collar 13 is rotated is very great, due to the slight resistance offered to the flow of the fluid from the openings 8, and to the constancy of the flow of the said fluid.

While I have shown and described the motor as employing the collar 13 having straight blades 14 for dislodging or removing scale or other deposit from tubes or other conduits, the collar and the blades may be substituted by other rotary supporting member and inclined vanes arranged to receive the streams of fluid emitted from the openings 8 and directed upon the inclined surfaces of the said vanes.

It is also evident that the flow of the fluid from the openings 8 past the blades 14 operate by pressure upon the surrounding medium to propel the motor forward, in the line of its work.

It will also be understood that any suitable fluid having pressure imposed thereon by any suitable means may be employed for operating the present motor.

105 Claims.

1. An apparatus as characterized comprising a hollow head having an unbroken front wall, and a rear wall having a centrally disposed receiving opening, and a series of delivery openings surrounding said receiving openings for delivering the fluid from said head in lines approximately par-

- allel to the fluid being delivered to said head; and rotative means disposed in the path of fluid delivered from said delivery openings to be rotated thereby.
5. An apparatus as characterized comprising a head embodying a hollow chamber, and a rearwardly extended tubular neck for delivering fluid to said chamber; and an unbroken front wall having an inwardly extended conical projection, the apex whereof coincides with the axis of said neck; and a series of rearwardly opening apertures for delivering the contents of said chamber in paths approximately parallel to said neck; a rotary driven member rotatively mounted on said neck, said member having radially extended abrasive members for operating in paths concentric to said neck.
6. An apparatus as characterized comprising a head embodying a hollow chamber, and a rearwardly extended tubular neck for delivering fluid to said chamber; and an unbroken front wall having an inwardly extended conical projection, the apex whereof coincides with the axis of said neck; a series of rearwardly opening apertures for delivering the contents of said chamber in paths approximately parallel to said neck; and a rotary abrasive member, said member embodying a collar rotatively mounted on said neck and having a series of inclined blades adapted to be deflected by the fluid delivered from said head; and abrasive members extended beyond the path of said fluid for operating on the side walls of a conduit through which said apparatus is moved.
7. An apparatus as characterized comprising a head embodying a hollow chamber and a rearwardly extended tubular neck for delivering fluid to said chamber; and an unbroken front wall having an inwardly extended conical projection the apex whereof coincides with the axis of said neck; a series of rearwardly opening apertures for delivering the contents of said chamber in paths approximately parallel to said neck; and a rotary abrasive member, said member embodying a collar rotatively mounted on said neck and having a series of inclined blades adapted to be deflected by the fluid delivered from said head; and abrasive members extended beyond the path of said fluid for operating on the side walls of a conduit through which said apparatus is moved, said abrasive members being integral with and extended from said blades.
2. An apparatus as characterized comprising a hollow head having an unbroken front wall, and a rear wall having a centrally disposed receiving opening, and a series of delivery openings surrounding said receiving opening for delivering the fluid from said head in lines approximately parallel to the fluid being delivered to said head; rotative means disposed in the path of fluid delivered from said delivery openings to be rotated thereby; and means carried by said rotative member for performing a desired function in paths concentric with the rotation of said rotary member.
3. An apparatus as characterized comprising a hollow head having an unbroken front wall, and a rear wall having a centrally disposed receiving opening, and a series of delivery openings surrounding said receiving opening for delivering the fluid from said head in lines approximately parallel to the fluid being delivered to said head; rotative means disposed in the path of fluid delivered from said delivery openings to be rotated thereby; and means carried by said rotative member for performing a desired function in paths concentric with the rotation of said rotary member, said means embodying a series of abrasive members mounted upon, and extending outward from said rotary member.
4. An apparatus as characterized comprising a hollow head having an unbroken front wall, and a rear wall having a centrally disposed receiving opening, and a series of delivery openings surrounding said receiving opening for delivering the fluid from said head in lines approximately parallel to the fluid being delivered to said head; rotative means disposed in the path of fluid delivered from said delivery openings to be rotated thereby; and means carried by said rotative member for performing a desired function in paths concentric with the rotation of said rotary member, said means embodying a series of abrasive members mounted upon, and extending outward from said rotary member, said blades being disposed in progressively increasing radial dimensions from said head backward.

SIDNEY C. SLADDEN.
